UNITED STATES PATENT OFFICE

ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY

RUFFLING MECHANISM FOR SEWING MACHINES

Application filed November 18, 1929. Serial No. 407,837.

This invention relates to sewing machine ruffler mechanisms and has for an object to provide a simplified form of treadle-controlled ruffler mechanism particularly adapted for application to a sewing machine having a lower horizontal main-shaft. According to the improvement there is mounted on the sewing machine gooseneck and upper ruffler-actuating rock-shaft disposed in a vertical plane offset from the lower main-shaft. The ruffler rock-shaft has fixed to it a curved crank-arm concentric with the main-shaft and extending toward the vertical plane of the main-shaft. The main-shaft is provided with an eccentric between the usual balance wheel and the vertical member of the gooseneck, and a vertical pitman embracing such eccentric is connected to the crank-arm on the ruffler rock-shaft. The connection in question is a frictional sliding one and the distance of such connection from the axis of the ruffler rock-shaft may be varied at the will of the operator, to vary the stroke of the ruffler blade. The treadle-control mechanism comprises a bell-crank lever fulcrumed on a bracket attached to the gooseneck and having a horizontal arm connected to a treadle-chain and a vertical arm connected by a link to the slide-block at the upper end of the ruffler-actuating pitman. The bracket which carries the treadle-controlled bell-crank lever also carries two vertically adjustable stops to limit the movement of the bell-crank lever and enable the operator to quickly shift from a predetermined long ruffler-stroke to a predetermined short ruffler-stroke.

Referring to the accompanying drawings, Fig. 1 is a side elevation of a sewing machine embodying the invention. Fig. 2 is a front end elevation of the machine. Fig. 3 is a rear-end elevation of the machine. Fig. 4 is a top plan view of the rear or balance wheel end of the machine. Fig. 5 is a section on the line 5—5, Fig. 3, and Fig. 6 is a section on the line 6—6, Fig. 1.

In the embodiment of the invention illustrated there is used a sewing machine having a bed 1, from which rises the standard 2 of the gooseneck including the over-hanging arm 3 terminating in the head 4 in which is

mounted the usual reciprocating needle-bar 5 and presser-bar 6 carrying, respectively, the needle 7 and presser-foot 8. The machine has a raised cloth-plate 9 below which and above the bed 1 is journaled the main-shaft 10, the outboard projection of which carries the ruffler-actuating eccentric 11 and balance wheel 12.

The ruffler mechanism adjacent the head 4 is old, per se, and comprises the usual separator-plate 13 above which works the ruffler-blade 14 pivotally carried at 15 at the lower end of the ruffler-arm 16 fixed to the forward end of the ruffler rock-shaft 17, which is journaled horizontally in bearings 18, 19, at the front side of the gooseneck in a vertical plane *p*, Fig. 3, offset to the left of the vertical plane *s* of the main-shaft 10. The rock-shaft 17 has fixed to it a curved crank-arm 20 which, in the advanced position of the ruffler-blade 14 is concentric with the axis of the main-shaft 10. The crank-arm 20 extends across the space between the planes *p* and *s* and is actuated by the vertical pitman 21 embracing the actuating eccentric 11.

Referring to Fig. 5, it will be seen that the pitman 21 is connected at its upper end to a yoke 22 connected by the pivot-pin 23 to the block 24 having a slide-way 25 for the curved arm 20. The upper sidewall of the slide-way 25 is constituted by an adjustable wear-plate 26 backed by the adjusting screw 27. The front side of the slide-way 25 is closed by a cap-plate 28 having a projecting pin 29 embraced by one end of the horizontal link 30 the other end of which is pivotally connected at 31 to the upstanding arm 32 of a bell-crank lever 32, 33 fulcrumed at 34 on the bracket 35 which carries the bearing 18. The arm 33 of the bell-crank lever extends forwardly and has connected thereto the treadle-chain 36. The recovery spring 37 coiled about the pivot screw 34 and anchored at its opposite ends to the arm 33 and bracket 35, respectively, urges the bell-crank lever to the short ruffle position shown in Fig. 3, when pressure upon the operating treadle is relieved.

Secured to the front face of the bracket 35 by the screw 38 is the slotted shank 39 of the

stop-arm 40 which is engaged by the bell-crank lever-arm 33 in the upward or recovery motion of the latter. The position of the stop 5 40 determines the amplitude of the short ruffle. Secured to the right-hand face of the bracket 35 by the screw 41 is the slotted shank 42 of the stop-arm 43 which limits the downward movement of the bell-crank lever-arm 33 and determines the amplitude of the long ruffle.

10 It will be observed that the stop-arms 40, 43, bell-crank lever 32, 33, spring 37, shaft 17 and arm 20 are all carried by the removable bracket 35, enabling them to be readily applied to or removed from the sewing machine and that the arrangement is simple and compact.

Having thus set forth the nature of the invention, what I claim herein is:

20 1. A sewing machine having a bed and gooseneck, a cloth-plate raised above said bed, a main-shaft journaled between said bed and cloth-plate, a ruffler-blade, a ruffler rock-shaft connected to reciprocate said blade and 25 journaled on said gooseneck, said rock-shaft being disposed in a vertical plane parallel to and offset from the vertical plane of the main-shaft, a crank-arm fixed to said ruffler rock-shaft and extending transversely of the 30 space between said planes, an eccentric on said main-shaft, an upstanding pitman the lower end of which embraces said eccentric and the upper end of which is connected to said crank-arm, and a treadle-controlled bell- 35 crank lever connected to shift the upper end of said pitman lengthwise of said crank arm.

2. A sewing machine having a cloth-plate and an overhanging gooseneck, a main-shaft journaled below said cloth plate, a ruffler 40 rock-shaft journaled on said gooseneck in a vertical plane displaced from the vertical plane of the main-shaft, a crank-arm fixed to the ruffler rock-shaft and extending across the 45 space between said planes, an eccentric on said main-shaft, a pitman connected at its lower end to said eccentric, a connecting element pivoted to the upper end of said pitman and slidably engaging said crank-arm, a treadle controlled bell-crank lever including 50 an upstanding arm, a link connection between said upstanding arm and said connecting element, and a ruffler-blade actuated by said ruffler rock-shaft.

3. A sewing machine having a bed and 55 gooseneck, a ruffler-blade, a ruffler rock-shaft, a bearing bracket for said rock-shaft detachably mounted on said gooseneck, a crank-arm fixed to said rock-shaft adjacent said bearing bracket, a main-shaft, an eccentric on said 60 main-shaft, a pitman connection between said eccentric and said crank-arm, a treadle-controlled bell-crank lever fulcrumed on said bracket and connected to shift the point of connection of the pitman with the crank-arm toward or away from the axis of said ruffler

rock-shaft, and stops adjustably mounted on said bracket to limit the movement of said bell-crank lever in opposite directions.

In testimony whereof, I have signed my name to this specification.

ANDREW B. CLAYTON.
